[57] CLAIM

The ornamental design for a water closet base, as shown.

DESCRIPTION

FIG. 1 is a top plan view of a water closet base showing my new design;

FIG. 2 is a side elevational view thereof;

FIG. 3 is an elevational view taken from one end thereof;

FIG. 4 is an elevational view taken from the end opposite that shown in FIG. 3; and

FIG. 5 is a cross-sectional view taken on line 5—5 of FIG. 1.

*Fig. 1.**Fig. 2.**Fig. 3.**Fig. 4.**Fig. 5.*
